UNITED STATES PATENT OFFICE.

EDWARD H. ELLIS, OF PASADENA, CALIFORNIA.

DESIGN FOR A CYLINDRICAL CABINET.

SPECIFICATION forming part of Design No. 28,033, dated December 14, 1897.

Application filed August 17, 1897. Serial No. 648,602. Term of patent 3½ years.

To all whom it may concern:

Be it known that I, EDWARD H. ELLIS, a citizen of the United States, residing at Pasadena, in the county of Los Angeles and State 5 of California, have invented and produced a certain new and original Design for Cylindrical Cabinets; and I do declare the following to be a full, clear, and exact description of the invention, such as will enable others skilled 10 in the art to which it appertains to make and use the same.

My invention relates to a cylindrical cabinet.

It relates to the entire configuration of the 15 cabinet, and especially to one of a vertical cylindrical form, as illustrated in the accompanying drawing, in which the figure is a perspective view of a cylindrical cabinet embodying my design.

20 In the following description the leading features or salient points of my design are enumerated.

1 represents the globular handle, the top 2 of which is formed of a convex shape greater

than the general convexity of the handle, 25 which is concentrically superimposed upon the top 6.

3 represents the vertical cylindrical body of the cabinet, and it is composed of vertical parallel panels of contrasting colors alternately arranged, as shown. The base of the handle terminates in a semicircular border projecting over and concentric with the body.

The base 4 of the body is also concentric therewith and terminates in a semicircular 35 flange 5, as shown, which is greater in diameter than the body portion.

Having thus fully described my invention, what I claim as new, and desire to secure by Design Letters Patent, is—

40 The design for a cylindrical cabinet, substantially as herein shown and described.

In testimony whereof I hereunto affix my signature in presence of two witnesses.

EDWARD H. ELLIS.

Witnesses:

JOHN S. COX,
WYNTER HIGLEY.
